CONVERTIBLE APPLIANCE STAND AND SERVICE TABLE

William I. Evans, Los Angeles, Calif.

Application August 21, 1944, Serial No. 550,363

4 Claims. (Cl. 211—2)

1

My invention relates to an appliance stand in shelf form and readily convertible into a service table or back into a service stand, as desired, and the objects of my invention are:

First, to provide a service stand with several open shelves which may be readily converted into a service table with flat top;

Second, to provide an apparatus of this class in which the shelves or tables are secured in their relation to each other when in either position for the appliance stand or service table;

Third, to provide an apparatus of this class wherein the table members are held in their aligned relation to each other and reinforced when in service table form;

Fourth, to provide an apparatus of this class which is readily convertible for either purpose, an appliance stand or a service table;

Fifth, to provide an apparatus of this class with novel latch means securing the apparatus in convertible position;

Sixth, to provide an apparatus of this class whereby objects on different members of the service table may remain there and be shifted so that they occupy substantially the same position on the appliance stand after it is converted from table to stand, or from stand to table; and

Seventh, to provide an apparatus of this class which is very simple and economical of construction, easy to operate and convert, efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application in which:

Figure 1 is a perspective view of my convertible appliance stand and service table in the appliance stand form; Fig. 2 is a similar view of the same in the service table form; Fig. 3 is an enlarged fragmentary side elevational view of the shiftable control bar and latch mechanism in relation therewith for securing the shelves and table in the position as shown in Fig. 1. Fig. 4 is an enlarged bottom view of one of the shelves with the control bar and bracket in connection therewith and Fig. 5 is an enlarged fragmentary side elevational view of the shiftable control bar and latch mechanism in position for holding the table and shelves in the position shown in Fig. 2.

2

Similar characters of reference refer to similar parts and portions throughout the several views of the drawing.

The side frame members 1 and 2, cross frame member 3, table and shelf members 4, 5 and 6, table and shelf connecting members 7 and 8, table and shelf shift control bar 9, shiftable latch member 10, shiftable latch control rod 11, and stationary latch member 12 constitute the principal parts and portions of my convertible appliance stand and service table.

The side members 1 and 2 are flat vertical plate like members of the proper height and preferably rounded at their upper corners at 1a and 2a.

15 Secured to the inner sides at the upper edge of each of these plates 1 and 2 is an L-shaped cross section member 1b which is secured to the plates with one of the members extending toward said plates leaving a space 1c, as shown best in Fig. 1 of the drawing. The outwardly extending ledge portion secured to these plates 1 and 2 is cut away at the one end to receive the table and shelf connecting members 7 and 8 when they are in vertical position, as shown in Fig. 1 of the drawing. Secured on the upper edges of the L-shaped member 1b and flush with the outer side leaving the groove 1c is the table or shelf member 5 which is the intermediate table or shelf member and is not shiftable.

20 The members 7 and 8 are pivotally mounted intermediate their ends in the slots 1c between the plates 1 at one side and the member 1b and table member 5 at the other side and between the side member 2 and table member 5 at the opposite side, all as shown best in Fig. 1 of the drawing. The opposite ends 1a and 8a are pivotally connected to the table or shelf members 4 and 5 at their opposite ends 7c and 8c. Thus the table or shelf members 4 and 6 are pivotally connected and supported relatively to the table member 5 by means of these connecting members 7 and 8 and are shiftable thereby to the two positions shown in Figs. 1 and 2 by manual operation by grasping the hand loop member 4a on the edge of the member 4, as shown in Figs. 1 and 2 of the drawing.

25 Mounted on the lower side of one edge of each of the members 4, 5 and 6 is a bracket member 4b, shown best in Fig. 4 of the drawing, and supported by screws 4c, which is provided with bifurcated extended portions between which the table and shelf shift control bar 9 is pivotally mounted by means of pins 9a.

30 Pivots mounted on this control bar 9 near its normally lower end is a latch member 10 which

is arranged to engage a stationary latch member 12 at its upper edge at one end and a notch 5a at its other end. This latch member 12 is secured on a cross frame member 3 connecting the side members 1 and 2 together near their lower sides at one edge, as shown best in Figs. 1 and 2 of the drawing.

Connected to the outer sides of the latch member 10 is latch member control rod 11 which is provided with a fixed washer 11a thereon and said rod extends through a bearing member 9c on the member 9 spaced from the latch member 10 some distance, and between the washer 11a and said bearing member 9c is the compression spring 11b which tends to hold the rod downwardly and the end of the latch 10 connected with the rod 11 in engaged relation with the latch member 12. This rod 11 extends to near the opposite end of the control bar 9 and adjacent to the hand member 4a, as shown best in Fig. 1 of the drawing. This rod 9 is supported on the bar 9 at the hand near the end member 4a by means of a loop 9c. Thus the end of the rod 11 is adjacent the hand member 4 so that the rod 11 may be drawn to release the latch member 10 from the member 12. At the same time the shelf member 4 may be drawn forwardly and the member 6 shifted backwardly until they reach the position shown in Fig. 2 of the drawing and they are secured in such relation by means of the portion 18c of the latch member 10 engaging the side of a hole 5a in the plate 5b mounted over a recess 5c in the table member 5 as shown in Fig. 5 of the drawing.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a convertible appliance stand and service table of the class described, the combination of two vertically disposed side members, an intermediate table member rigidly secured thereto at their upper edges and spaced from the inner sides thereof, a pair of table connecting members interposed between said intermediate table member and said side members at one side thereof and pivotally mounted thereon intermediate their ends, a pair of shelf members each pivotally connected near one side edge of each shelf member near opposite ends of said connecting members, and a single shift control bar pivotally connected to said shelf members at their middle opposite edge from said connecting members and latch means in connection therewith.

2. In a convertible appliance stand and service table of the class described, the combination of two vertically disposed side members, an intermediate table member rigidly secured thereto at their upper edges and spaced from the inner sides thereof, a pair of table connecting members interposed between said intermediate table member and said side members at one side thereof and pivotally mounted thereon intermediate their ends, a pair of shelf members each pivotally connected near one side edge of each shelf member near opposite ends of said connecting members, a single shift control bar pivotally connected to said shelf members at their middle opposite edge from said connecting members, and latch means mounted on said control bar for holding said shelf members in certain relation to each other.

3. In a convertible appliance stand and service table of the class described, the combination of two vertically disposed side members, an intermediate table member rigidly secured thereto at their upper edges and spaced from the inner sides thereof, a pair of table connecting members interposed between said intermediate table member and said side members at one side thereof and pivotally mounted thereon intermediate their ends, a pair of shelf members each pivotally connected near one side edge of each shelf member near opposite ends of said connecting members, a single shift control bar pivotally connected to said shelf members at their middle opposite edge from said connecting members, and latch means mounted on said control bar for holding said shelf members in certain relation to each other, said latch means being operable from near one end of said connecting member and arranged to shift the latch near the opposite ends thereof.

4. In a convertible appliance stand and service table of the class described, the combination of two vertically disposed side members, an intermediate table member rigidly secured thereto at their upper edges and spaced from the inner sides thereof, a pair of table connecting members interposed between said intermediate table member and said side members at one side thereof and pivotally mounted thereon intermediate their ends, a pair of shelf members each pivotally connected near one side edge of each shelf member near opposite ends of said connecting members, a single shift control bar pivotally connected to said shelf members at their middle opposite edge from said connecting members, latch means mounted on said control bar for holding said shelf members in certain relation to each other, said latch means being operable from near one end of said connecting member and arranged to shift the latch means near the opposite ends thereof, and a stationary latch means in connection with said side members.

WILLIAM I. EVANS.
